UNITED STATES PATENT OFFICE.

ELIJAH S. GILMORE, OF SAN FRANCISCO, CALIFORNIA, ASSIGNOR OF TWO-THIRDS TO NATHAN W. SPAULDING, OF SAME PLACE.

BAND SAWING-MACHINE.

SPECIFICATION forming part of Letters Patent No. 406,396, dated July 2, 1889.

Application filed June 16, 1887. Renewed November 30, 1888. Serial No. 292,331. (No model.)

To all whom it may concern:

Be it known that I, ELIJAH S. GILMORE, a citizen of the United States, residing at San Francisco, in the county of San Francisco and State of California, have invented certain new and useful Improvements in Band Sawing-Machines; and I do hereby declare that the following is a full, clear, and exact description of my said invention, reference being had to the accompanying drawings, that form a part of this specification.

My invention relates to improvements in driving and guiding endless band-saws, and it embraces several novel points and features of mechanism for the better control of the saw in band sawing-machines, as hereinafter described, and pointed out in the claims.

The first part or feature consists of saw-deflecting rollers having lateral adjustment, and mechanism whereby the same is brought under the control of the sawyer for regulating the saw while the machine is at work.

The second part of my improvements embraces deflecting-rollers having vertical adjustment in arcs that throw their planes of rotation and contact diagonally across the face of the saw, by virtue of which position they act upon the saw to throw the cutting-edge forward or to draw it back from the wood while running. In connection with this part of my invention provision is made for producing this movement of the rollers automatically by or from the saw itself, whereby the line of the cutting-edge is kept up to its work against its tendency to run back from the wood.

The improvements include also the combination, with an endless band-saw, of an indicating device to show the true vertical position of the cutting-edge and to indicate the degree of its departure from such position at all times during work.

The following description fully explains the nature of these said improvements and the manner in which I construct, apply, and carry out the same, the accompanying drawings being referred to by figures and letters.

Figure 1 of the drawings is a front elevation of a band-saw, its carrying-wheels, and portions of the frame and table with my improvements applied thereto. Fig. 2 is a side

view of the saw, the carrying-wheels, and the belt and pulleys connecting one wheel with the other. Fig. 3 is a front view of the deflecting-rollers and an adjusting mechanism. 55 Fig. 4 is a side view taken from the right-hand side of Fig. 3. Fig. 5 is a top view of the upper set of rollers, showing the manner of mounting them on the movable bracket. Fig. 6 is a perspective view of the lower set 60 of rollers and connected mechanism for adjusting them laterally and in vertical arc. Fig. 7 is a side view of the two sets of rollers and the connections to move them simultaneously. Figs. 8, 9, and 10 show the indicator 65 in front view and in detail and illustrate its operation.

A A are two pulleys fast on the shafts or centers b of the saw-carrying wheels B B, to take the belt C, by which the two wheels are 70 connected.

D is the saw, and E is a small pulley set in position on the frame about midway between the two carrying-wheels to take the belt and guide it away from the front or cutting portion of the saw. Suitable tension is kept on the belt by this pulley through the connection of its slide E² to a weight E^X, the slide being mounted in a grooved plate E³, bolted to the upright timbers of the frame, and the 80 weight being attached by a rope running over the pulley E⁴.

The plate G, with a dovetail slot or way, is secured to the face of the column or post of the machine as a support for the bracket H, 85 the back plate h of which is fitted to the slot to slide up and down in this support. This movement is effected by a screw-shaft I, and by such means the upper set of deflecting-rollers is adjusted up or down to regulate 90 the distance between the two sets. The screw-shaft turns in a fixed bearing k^X, and works in a socket in the bracket, a hand-wheel K being provided on its end for turning it.

To deflect the saw to one side or the other 95 the two sets of rollers L L L^X L^X are mounted on blocks or carriers M M, that are capable of longitudinal movement, and by properly connecting the carriers together equal and simultaneous adjustment of the top and bottom sets 100 of rollers in a lateral direction is obtained. In addition to this lateral movement, the rollers

of each set are adjustable in vertical arcs, by which they are elevated or depressed from the horizontal into a diagonal position across the face of the saw, and these two adjustments are 5 made separately and independently, but also simultaneously and equally in the two sets of rollers by means of the two rods R S and connecting mechanism, the general construction and arrangement of which will be understood 10 from the detail views, Figs. 3, 6, and 7.

The rollers are set on studs m^x , and the block M, in which they are fixed, is capable of sliding laterally in the supports $h^2 h^3$. The block is secured to the rod m at one end, and 15 is provided with a stud m^4 at the opposite end to fit the bearing h^2 . On these supports as centers the block is also capable of turning in a vertical arc, and these two movements, laterally in a horizontal plane and 20 perpendicularly in a vertical plane, are produced by moving the rod m longitudinally and by turning or partly rotating it in its bearings. These are effected from the two 25 upright rods R S, the first one of which is free to be turned in supports on the frame, and is furnished with a hand-lever working over a locking-segment for turning it, and the other of which is capable of being moved vertically 30 in its supports, this movement being produced by the rotation of a screw-threaded sleeve turning loosely on the rod between collars, and working through a stationary nut U on the bracket H. The fixed collars S^x above and beneath the sleeve confine it on 35 the shaft, and the hand-lever T^x serves for turning it. Such rotation of the sleeve T causes the rod to slide up or down, and by connecting the rock-shafts m by arms to this rod S its vertical movement turns the blocks 40 M on their center. The rod R is connected directly to the rock-shaft m by means of a spline R^2 on one and the groove V^2 in the other at those parts of the two shafts that set against or across each other. Partial rotation of the 45 rod R therefore moves the rod or shaft n longitudinally. Both sets of rollers being connected in this manner with the two upright shafts or rods, an equal movement is produced in both when the lever R^x or the lever T^x is turned. 50 By the first-mentioned lever and its rod the two carriers M M^x are shifted laterally to deflect the saw, and by the other lever and rod the rollers are elevated or depressed toward or from a horizontal or perpendicular plane 55 with respect to the plane of the saw in greater or less degree to assume a horizontal position, or one diagonal with reference to the plane of rotation. By virtue of such diagonal position the rollers act upon the saw running 60 between them to throw the cutting-edge forward or to draw it away from the wood, the saw being influenced in the one case by the elevation of the rollers and in the other by depressing them below the horizontal. The 65 rollers are faced with rubber or other suitable material, and the stud of one roller is adjustable to and from the other stud to regulate

the contact and grip upon the saw. The stud is fixed for this purpose in a sliding box m^2 , held by set-screws m^3 .

The arms V have forked ends with pivot-screws taking in collars U^x on the shaft, and each collar is either fixed to the shaft by a set-screw U^2 , or it is confined and allowed to have a limited movement independent of the 75 shaft by placing a spring S^2 above and one below the collar. These two springs are of about equal tension, are held and their tension is regulated by movable collars $t t$ to exert equal pressure or resistance against the 80 collar U^x , or by setting them down to the point of greatest compression of the spring the collar may be practically locked to the shaft. It is also fixed in some cases by the set-screw U^2 . The office of these springs is 85 to afford a limited movement of the deflecting-rollers independently of the rod S, so that by fixing upon the front of the roller-carrier a stop N in a position to take or be struck by the back edge of the saw the carrier may be 90 turned on its centers and the rollers set up or down on a vertical arc accordingly by the contact and pressure of the saw itself. This action will be understood by referring to Figs. 95 5, 6, and 7.

The stop N is a tube slotted at the front and filled with a packing of some suitable substance, such as a piece of tarred rope. It is fixed rigidly to the block M to stand in line with the space between the rollers, and is, 100 with respect to the axes of the rollers, set a little out of the perpendicular to present one end in advance to meet the edge of the saw. In such position the pressure of the saw in running back against the stop will tend to 105 bring it up to the vertical, and this movement affecting the roller-carrier M will cause it to turn on its centers, the result of which will be to throw the rollers out of the horizontal and set them diagonally across the face of the saw. The arms V are therefore required to yield at the points of attachment to the 110 upright rod, and this movement is permitted by the arrangement of collars and springs, as before described.

While the back of the saw is clear of the stop the rollers stand horizontally, and their plane of contact and rotation coincides with the vertical plane in which the saw travels; but as soon as the cutting-edge departs from 115 a given line and runs back sufficiently to bring the back edge up against the stop the rollers will be thrown up from the horizontal, and by virtue of their diagonal position during rotation will counteract this backward 120 movement and throw the saw forward. Therefore, by setting the stop in this manner and placing springs on each side of the collar U^x , the adjustment of the rollers in a vertical arc is made automatic, and the saw readjusts itself when out of line. The true vertical position is also dictated to the sawyer by a pointer vibrating in front of a dial or graduated arc, so that the saw can be kept up to its 125

work by means of the hand-lever and connecting mechanism without making use of the automatic device, if so desired. In such case the collars U^x are fixed to the rod S by means of the set-screws U^2 , and the arms V are moved only as the rod S is moved by the hand-lever. This, however, necessarily calls for closer attention on the part of the sawyer, but is readily done while the machine is running. In applying this indicator I set a yielding finger Y on a shaft behind the saw in position to bear against the edge of the blade while the saw is at work, and connect to this shaft the end of a pivoted pointer Z in such manner that the rotary movement produced by the rise and fall of the finger will throw the pointer in an arc from the center. This connection I have made by fixing a plate with an inclined slot or groove y^2 on the shaft in front of the pointer and setting the extension of the pointer below the pivot into this slot. The construction and operation of this connection will be understood from Figs. 8, 9, and 10.

On the front of the bracket in Figs. 4 and 7 will be noticed a slotted plate P with a thumb-screw P^x working through the slot and into the side of the arm V directly behind the plate. The office of this attachment is to hold the arm V while the bracket is being moved up or down in changing the height of the upper rollers from the lower set. In such adjustment it becomes necessary to loosen the collars U^x on the rod S , in order that the arm V may slide on the rod as the bracket is moved. At such time the adjusting is more readily effected if the arms V are set and held in parallel position, and for this purpose the slotted plate and screw are applied, as before described. The plate is secured to the bracket H , and the slot in it is of suitable length to let the screw play loosely up and down in it when the end of the arm is attached to the rod S and the mechanism is at work.

In the operation of setting the bracket up or down both sets of rollers are placed so that arms V are parallel, and then the screw P^x is tightened to fix the top arm before the collars are loosened on the rod S .

The parts being constructed and combined in a machine as thus described, operate to perfectly guide and control the saw under the conditions of great speed at which such machines are run. The advantages incident to their use will be clear to those persons familiar with running and handling band-saws.

In an application filed by me on the 3d day of January, 1889, Serial No. 295,359, claims to the following features (which are shown in this application) are made, viz: a regulating attachment consisting of two rollers adapted to grip the saw-blade between them and capable of angular adjustment with respect to the plane in which the saw-blade runs, whereby they can be set to rotate at an angle across the saw-blade, in combination with means for

setting and holding the rollers at different angles across the saw-blade, and the combination with a band-saw, a pair of gripping-rollers adapted to embrace and run with the saw-blade and mounted in a tilting frame or carrier which is capable of adjustment to change the angle of rotation of the rollers with respect to the plane in which the saw runs, and mechanism connected with said tilting carrier for setting it at different angles of elevation and depression. I therefore do not make such claims herein.

Having thus fully described my invention, what I claim, and desire to secure by Letters Patent, is—

1. In a band sawing-machine, the combination, with two sets of laterally-adjustable deflecting-rollers, of rods m , by which the rollers are adjusted, and the upright rods R and S , connected to rods m , in the manner and for the purpose set forth.

2. In a band sawing-machine, the combination of the two sets of deflecting-rollers and pivoted carriers on which the rollers are mounted, said carriers being capable of being elevated or depressed in similar vertical arcs, rods m , connected to the carriers, and upright rods R and S , connected to the rods m , in the manner set forth, whereby the vertical movement of the carriers is produced and the sets of rollers are set-simultaneously and equally, as set forth.

3. In a band sawing-machine, the combination of deflecting-rollers, a sliding carrier on which they are mounted, rod m , connected to said carrier, and upright rod R , connected to rod m , in the manner and for the purpose set forth.

4. The combination of the pivoted and sliding roller-carrier M , rod m , connected thereto, arm V , secured upon rod m and having the groove V^2 , and the upright rod R , having a spline R^2 working in groove V^2 , and the upright rod S , to which one end of the arm V is connected, in the manner and for the purpose set forth.

5. The combination of the pivoted roller-carriers M , rods m , connected thereto, arms V , secured upon rods m , rods S , to which the arms V are connected at their opposite ends, and the screw-threaded sleeve T and fixed nut U on rod S , as a means for moving said rod, as set forth.

6. The combination of the sliding roller-carrier M , rod m , connected thereto, having a groove V^2 in it or in a part fixed upon it, and the upright rod R , having a spline R^2 , working in the groove, as set forth.

7. The combination, with the pivoted roller-carriers M , of the rods m , connected thereto, arms V , secured upon rods m , the rod S , the yielding collars U^x , by which the arms V are connected to the rod S , and the stop N , against which the back of the saw works, as set forth.

8. The combination, with an endless band-saw, of an indicator adapted to show the true

vertical position of the saw and to indicate the degree of its departure therefrom, consisting, essentially, of a pointer, a scale or dial, and a finger bearing against the saw and 5 connected with the pointer to operate the same by or from the movement of the saw, as set forth.

9. The combination, with the roller-carriers M, rods *m*, connected thereto, arms V, secured 10 upon rods *m*, and rod S, to which the arms V

are connected, of the clamp-screw and slotted plate P, through which the clamp-screw passes to the arms V, as and for the purpose set forth.

In testimony that I claim the foregoing I 15 have hereunto set my hand and seal.

ELIJAH S. GILMORE. [L. S.]
